UNITED STATES PATENT OFFICE.

CHARLES HENRY FOX, OF BAKERSFIELD, CALIFORNIA.

PUMP.

1,201,954.

Specification of Letters Patent. Patented Oct. 17, 1916.

Application filed December 31, 1915. Serial No. 69,648.

To all whom it may concern:

Be it known that I, CHARLES H. FOX, a citizen of the United States, residing at Bakersfield, in the county of Kern and State of California, have invented a new and useful Pump, of which the following is a specification.

This invention has reference to pumps, and its object is to provide a means for elevating water by the direct effect of explosive mixtures, especially those of a hydrocarbon and air.

The invention comprises one or more explosion chambers to be located at a low point in the well, and means for conducting an explosive mixture from the surface of the ground to the explosion chamber or chambers and for igniting the mixture at the surface of the ground with the ignition progressing through what may be termed a fuse pipe to the explosion chamber, whereby the gases of explosion are utilized to raise the water to the surface of the ground.

The invention also comprises numerous features which will be set forth in detail in the more specific description to follow.

The invention will be best understood from a consideration of the following detailed description taken in connection with the accompanying drawings forming part of this specification, with the further understanding—that while the drawings show a practical form of the invention, the latter is not confined to any strict conformity with the showing of the drawing, but may be changed and modified so long as such changes and modifications come within the scope of the appended claims.

In the drawings:—Figure 1 is a more or less diagrammatic representation, with some parts in elevation, of a pump system embodying the present invention. Fig. 2 is a longitudinal diametric section with some parts in elevation of the portion of the pump structure designed to be located deep in the well. Fig. 3 is a plan view of the pump structure of Fig. 2 with some parts in cross-section and the up-take pipe omitted. Fig. 4 is a section on the line 4—4 of Fig. 2. Fig. 5 is a section on the line 5—5 of Fig. 2 with some parts shown in elevation, and with the casing and up-take pipe omitted. Fig. 6 is a section on the line 6—6 of Fig. 2. Fig. 7 is a section on the line 7—7 of Fig. 2.

Fig. 8 is a detail section of an automatic check valve controlling the supply of explosive mixture and neutral air.

Referring to the drawings there is indicated a well 1 provided with a casing 2 and may be taken as indicative of any suitable well, and especially a deep well. Near the bottom of the well there is a pump casing 3 which may be shaped to define two oval members 4, 5, joined intermediately. Centrally located within the members 4 and 5 are cylinders 6 and 7, respectively. Above the cylinders 6 and 7 the two members 4 and 5 have continuations 8 and 9, respectively, terminating in contracted passages 10, 11, opening into a pipe 12 constituting the up-take pipe and leading to the surface of the ground and from such point to any suitable point of disposal of the water to be elevated, which water is directed through the pipe 12 in a manner which will hereinafter appear. Within the pipe 12 adjacent to the passages 10, 11 is a valve 13 of any suitable construction, the valve being indicated as an ordinary flap valve without limitation to such particular form of valve.

At the lower ends the two members 4 and 5 of the pump casing are formed into necks 14, 15, respectively, into each of which is screwed a cage 16 having a central guide 17 and terminating at the top in a valve seat 18, it being understood that the parts are upright in the installed position. In the respective necks 14, 15 are located foot valves 19, 20, respectively, adapted to the valve seats 18 and each having a stem 21 extending through the guide 17 and at the lower end carrying a float 22. Each cylinder 6 and 7 has a contracted lower end 23 with a passage 24 therethrough opening into the interior of the member 4 or 5, as the case may be. The contracted end 23 constitutes an abutment for the respective valve 19 or 20 preventing the float 22 from rising to an extent to close the entrance to the lower end of the casing member 4 or 5 through the cage 16. Each cylinder 6 and 7 is closed at the upper end by a head 25 and within each cylinder is a piston 26 having an axially extended stem 27 at the lower end terminating in a valve adapted to close the passage 24 when the piston 26 is in its lowermost position. The upper end of each piston 26 is dished or cupped, as shown at 28, for a pur-

pose to be described, and leading axially from the cup is a passage 29 for a part of the distance through the piston. At the lower end of the passage 29 are branch passages 30 leading to a circumferential channel containing a packing ring 31. The upper ends of the interiors of the cylinders 6 and 7 are connected by a passage 32 in turn connected to a pipe 33 leading to the top of the well and serving a purpose to be described. Near the connection of the pipe 33 with the passage 32 the pipe contains a check valve 34 opening toward the passage 32.

15 Connecting to each cylinder 6 and 7 is a pipe 35 containing a check valve 36 close to where the pipe 35 connects with the cylinder, and such connection is so located that the pipe opens into the cylinder below the 20 piston 26. Each pipe 35 leads to the top of the well.

The pipes 35 are designed to conduct an explosive mixture, put under compression by means to be described, to each cylinder 6 25 and 7 below the piston 26 therein. The pipe 33 is designed to conduct air under pressure to each cylinder 6 and 7 above the piston 26 therein. The mixture conveyed by the pipes 35 may be a mixture of air and hydrocarbon 30 gas in proper proportions to produce an explosive mixture, while the air supplied by the pipe 33 is free from admixture with hydrocarbon and to distinguish the air supplied by the pipe 33 from the mixture supplied by the pipes 35, such air may be termed 35 neutral air.

When the pump casing 3 is immersed in the water in the well, the floats 22 tend normally to rise, thus opening the valves 19 and 40 20 and under such circumstances water will flow into the interior of the casing 3 about the cylinders 6 and 7 to and through the openings 10 and 11, raising the valve 13 and flowing into the pipe 12 to the level of water 45 in the well. Suppose now that an explosive mixture is supplied to the pipes 35 under some predetermined pressure, and that neutral air is supplied to the pipe 33 under like pressure, the pistons 26 being, because of 50 their weight, in the lower position so that the openings 24 are closed by the valve ends of the stems 27. The pressure of explosive mixture entering the cylinders 6 and 7 below the pistons and the pressure of air entering 55 the cylinders above the pistons may be considered as about equal, with the area exposed to pressure greater above than below the piston, wherefore the pressure of explosive mixture may rise in the cylinders 60 until a sufficient pressure is established therein without opening the valves. Now, when the compressed charge is ignited in pipe 35, there is thereby produced a progressive increase of compression advancing ahead of 65 the ignited gas as it goes from the spark-

plug to the chamber below the piston. This progressive increase of compression may be utilized to ignite the charge in the chamber below the piston, by compression. With the pipe 35 of large enough diameter, the compression in the chamber below the piston can be raised to any pressure desired. It is only when the pressure within the explosion chambers in the cylinders 6 and 7 below the pistons 26 rises higher than the pressure 70 above the pistons that the valves may open. This rise of pressure in the explosion chamber occurs when the explosive mixture is ignited, and then pressure within the explosion chamber rises very high, thus lifting the piston and further compressing the air above the piston, so that such air acts as an elastic buffer preventing the sudden impulse of the explosion from driving the piston violently against the upper head of the 80 cylinder and acting to return the piston to its lowest position. The highly increased pressure thus produced above the piston is not communicated to the pipe 33 because of the presence of the check valve 34. Nor is 90 the pressure of the explosion within the particular cylinder, say, the cylinder 6, under consideration communicated to the pipe 35 supplying explosive mixture to the cylinder, because of the presence of the check valve 36. 95

The gases of explosion escape through the passage 24 then opened by the rise of the valve with the piston 26 and force the valve 19 to the closed position shown in Fig. 2 and the gases of explosion then acting upon 100 water within the interior of the member 4 of the casing 3 drive such water out of the member 4 through the opening 10 and acting on the valve 13 raise the latter, thus forcing the water within the member 4 into the pipe 12, a proportion of the gases of explosion following the water into the pipe 12, whereupon the buoyancy of the gases together with the next explosion continues the lifting of the water to the point of discharge. In 105 the meantime the explosive mixture has been accumulating within the cylinder 7 below the piston 26 therein, and at the proper time such gases are ignited, exploded and force water into the pipe 12 in the same manner 110 as has been described with reference to the cylinder 6. The pressure caused by the first explosion rapidly diminishes, so that the piston in the cylinder 6 is no longer sustained by the superior pressure on its lower end, 115 and consequently the piston drops until the valve 27 is in the closed position and the cylinder is again charged with explosive mixture, this occurring while the explosion is taking place in the cylinder 7 and the 120 pressure therein is diminishing. As soon as the valve 27 in the cylinder 6 is closed the pressure within the member 4 has sufficiently reduced to permit the valve 19 to open under 125 the buoyancy of the float 22, and the par- 130

tial vacuum formed in member 4, so that the member 4 again becomes filled with water.

The operations occur in succession, and water is forced alternately through the openings 10 and 11 into the pipe 12. When these operations follow each other in quick succession the valve 13 remains in the open positions, but when the operations follow each other comparatively slowly, the valve 13 may close, or approach the closed position after each explosion.

In order that the pistons 26 may be kept lubricated, a small amount of lubricating oil is fed through the pipe 33 and through the passage 32 into the cylinders 6 and 7 above the pistons 26. The cupped or dished ends 28 of the pistons serve to collect the lubricating oil reaching the cylinders and to direct such oil through the passages 29, from which the oil is distributed by the passages 30 to the grooves receiving the packing rings 31.

The pump of the present invention after being lowered into the well requires no attention for long periods of time. The only moving parts are the pistons and buoyant valves 19, 20, for the means for igniting the charges is located on top of the ground where such means is at all times readily accessible.

One of the structures whereby explosive mixture and neutral air are supplied to the pump and the explosive charges are ignited, is shown in Figs. 1 and 8. At some convenient point there are provided two pumps 35^a, 36^a which may have pistons connected together by a piston rod 37 to be driven simultaneously by any suitable source of power. Such driving means are not shown in the drawings, since they may consist of any of the frequently used devices for the purpose, a one or one and one-half horse power gasoline engine giving excellent results for supplying a pump with fuel and air even though the pump be of large capacity. Of course, other types of motors may be used. The fuel is supplied to the pump 35^a through a carbureter 38, which latter may be of any suitable type, and, therefore, is not shown in detail. Between the carbureter 38 and pump 35^a is a check valve 39 and on the discharge side of the pump 35 is another check valve 40, the latter opening into a T coupling 41 connected through certain fittings and other structures to the pipes 35. The fittings and structures include an automatic check valve 42 of special construction, an ordinary check valve 43, a T 44 carrying a spark plug 45, still another ordinary check valve 46, and a T coupling 47, the latter having its stem portion connected through a check valve 48 to a pump 49 having a piston rod 50 which may be driven by the same power employed

to drive the piston rod 37. The pump 49 is fed with water through a pipe 51 and its purpose is to supply a spray of water to the pipe 35 to which it is connected, which water ultimately finds its way into the respective cylinder 6 or 7, as the case may be, thus providing a water seal at the valve end of the stem 27 and aiding in preventing leakage at such valve during the introduction of the charge of explosive mixture into the cylinder into which the pipe 35 opens. The T 41 has its stem connected to another T 52 connected by a pipe 53 to the pump 36^a. Air is drawn into the pump 36^a through a check valve 54 and escapes from the pump 36^a through another check valve 55 opening into the pipe 53. The coupling 52 is connected by a pipe 56 to the automatic check valve structure 42 and to this structure at a point opposite the pipe 56 the pipe 33 is connected. Within the valve structure 42 is a piston 57 having a passage 58 diametrically therethrough. The piston 57 is urged by a spring 59 within the check valve 42 to such position that the passage 58 coincides with the pipes 33 and 56, but should the pressure within the pipe 35 and parts connected thereto rise above the tension of spring 59, the latter is compressed and the piston 57 moves to an extent to close communication between the pipes 33 and 56, whereupon air supplied by the pump 36^a to the pipe 53 then flows to the pipe 35.

With means for supplying explosive mixture and neutral air to the cylinders 6 or 7, such means being duplicated in so far as necessary for supplying two cylinders 6 and 7, the explosive mixture supplied through the carbureter 38 is forced by the pump 35^a to the pipe 35 through the various check valves and parts interposed between the pump 35^a and the pipe 35. At the same time neutral air is supplied by the pump 36^a to the pipe 33. Since the pressures are alike in the two pipes no admixture takes place. When the cylinder being supplied, say, the cylinder 6, is filled with explosive mixture in its explosion chamber up to the desired pressure, and neutral air to a like pressure has been introduced into the cylinder above the piston 26, the compressed explosive mixture is fired at the spark plug 45. This immediately establishes pressure sufficient to close the check valve 43 so that there can be no back fire toward the carbureter but the burning of the explosive mixture progresses through the pipe 35 to the explosion chamber of the cylinder 6, wherefore the pipe 35 becomes a fuse pipe. Furthermore, the pressure exerted by the explosion closes the check valve 48. As soon as the force of the explosion is exhausted the pump 49 sprays water into the pipe 35, thus aiding in cooling the pipe which has become heated by the gases of explosion and liability of premature ex-

losion at the next charge is avoided. Furthermore, the water pumped into the pipe 35 flows down the latter to the cylinder 6 and as the valve 27 moves to the closed position the water accumulates about it, thus providing a water seal where the valve 27 seats at the passage 24, the lower end of the cylinder 6 or 7, as the case may be, being of taper or other shape to facilitate the accumulation of water about the valve.

Suppose that for some reason the charge within the cylinder 6 or 7 fails to explode. Then as the next charge is forced toward such cylinder it means a more compressed charge, so that the pressure within the pipe 35 rises above the tension of spring 59 sufficiently to act upon the piston 57 in a manner to move it to carry its passage 58 out of coincidence with the pipes 53 and 56. Under these circumstances the neutral air is forced into the pipe 35, since the pipe 33 is cut out of communication with the pump 36. The result is that the pressure within the explosion chamber of the particular cylinder 6 or 7 is increased beyond that of the neutral air and the piston 26 is raised to open the valve 27 and permit the escape of accumulated gas within the explosion chamber even though there has been no explosion.

If but one of the cylinders 6 or 7 be utilized the pump will operate as a single acting pump, while if both cylinders 6 and 7 be utilized to operate alternately the pump will operate as a double acting pump and the stream of water will then be substantially continuous instead of intermittent.

The pump casing 3 may in large part be of a single casting, thus contributing to the simplicity, strength and cheapness of manufacture of the device. The piping and fittings are in most part of commercial type and are largely purchasable in the open market.

What is claimed is:—

1. In an apparatus for raising water from wells or other places, a pump cylinder adapted to be immersed in the water, a reciprocating piston in the pump cylinder provided with a valve controlled by the piston and in turn controlling the outlet of the pump cylinder, means for introducing an explosive mixture into the pump cylinder on the valve side of the piston, and means for supplying air under pressure to the pump cylinder on that side of the piston remote from the valve.

2. In an apparatus for raising water from wells or other places, a pump cylinder, a reciprocating piston therein and provided with a valve for controlling the outlet of the cylinder, means for supplying air under pressure to one end of the piston, means for supplying an explosive mixture to the pump cylinder at the other end of the piston, said last-named means being in the form of a

pipe leading to and above or beyond the top of the well, and means for igniting the explosive mixture in said pipe at or above or beyond the top of the well, whereby the pipe for conducting the explosive mixture to the cylinder serves as a fuse pipe for igniting the explosive mixture within the explosion chamber of the pump cylinder.

3. In an apparatus for raising water from wells or other places, a pump casing having a foot valve for the admission of water therein and an outlet for the escape of water therefrom, said casing also having a pump cylinder therein between the foot valve and the outlet end of the casing, a reciprocating piston within the cylinder having a valve at one end and said cylinder having an outlet controlled by the valve, means for supplying an explosive mixture to the cylinder on the valve side of the piston, and means for supplying air under pressure to the cylinder on that side of the piston remote from the valve.

4. In an apparatus for raising water from wells or other places, a pump casing having a foot valve at one end and an outlet at the other and also provided with a cylinder within the casing between the foot valve and the outlet end of said casing, a reciprocable piston within the cylinder with a valve on said piston and the cylinder having an outlet toward the foot valve controlled by the valve of the piston, means for supplying an explosive mixture to the cylinder on the valve side of the piston, and means for counterbalancing the pressure of the explosive charge.

5. In an apparatus for raising water from wells or other places, a pump casing having a foot valve at one end and an outlet at the other and also provided with a cylinder within the casing between the foot valve and the outlet end of said casing, a reciprocable piston within the cylinder with a valve on said piston and the cylinder having an outlet toward the foot valve controlled by the valve of the piston, means for supplying an explosive mixture to the cylinder on the valve side of the piston, and means for counterbalancing the pressure of the explosive charge, said counterbalancing means comprising a pipe leading into the cylinder on the side of the piston remote from the valve.

6. In an apparatus for raising water from wells or other places, a pump casing having a foot valve at one end and an outlet at the other and also provided with a cylinder within the casing between the foot valve and the outlet end of said casing, a reciprocable piston within the cylinder with a valve on said piston and the cylinder having an outlet toward the foot valve controlled by the valve of the piston, means for supplying an explosive mixture to the cylinder on the

valve side of the piston, and means for counterbalancing the pressure of the explosive charge, said counterbalancing means comprising a pipe leading into the cylinder on the side of the piston remote from the valve, and the means for supplying the explosive mixture to the cylinder comprising a pipe constituting both a feed pipe and a fuse pipe and having means at a point distant from the cylinder for igniting the charge in said cylinder.

7. In an apparatus for raising water from wells or other places, a pump casing adapted to be immersed in the water in the well, said casing having an inlet at the lower end and an outlet at the upper end and also provided with an interior cylinder provided with an outlet at the lower end, a float valve constituting a foot valve for the inlet to the casing, 15 a reciprocable piston in the cylinder within the casing and having a valve controlling the outlet of the cylinder, a pipe communicating with the cylinder below the piston and constituting a means for introducing an explosive mixture therein, and another pipe communicating with the cylinder above the piston and constituting a means for supplying air under pressure to counteract the lifting effect of the explosive mixture fed to the 20 pump cylinder through the first-named pipe.

8. An apparatus for raising water from wells or other places, comprising a pump casing with an inlet at the lower end and an outlet at the upper end, a pipe communicating with the outlet and leading to the top of the well, a float valve constituting a foot valve for the casing, a cylinder within the casing having an outlet at its lower end directed toward the foot valve, a reciprocable 35 piston within the cylinder and carrying a valve for the outlet of said cylinder, a pipe leading to the top of the well and communicating with the cylinder below the piston, another pipe leading to the top of the well, 40 and communicating with the cylinder above the piston, means for supplying the first-named pipe with explosive mixture, and means for supplying the second-named pipe with air under pressure.

50 9. An apparatus for raising water from wells or other places, comprising a pump casing with an inlet at the lower end and an outlet at the upper end, a pipe communicating with the outlet and leading to the top of the well, a float valve constituting a foot valve for the casing, a cylinder within the casing having an outlet at its lower end directed toward the foot valve, a reciprocable 55 piston within the cylinder and carrying a valve for the outlet of said cylinder, a pipe leading to the top of the well and communicating with the cylinder below the piston, another pipe leading to the top of the well, 60 and communicating with the cylinder above the piston, means for supplying the first-

named pipe with explosive mixture, and means for supplying the second-named pipe with air under pressure, means located at or above or beyond the upper end of the well for igniting the explosive mixture within the first-named pipe, and means for supplying said first-named pipe with water for cooling purposes and for producing a water seal about the piston carried valve. 70

10. An apparatus for raising water from wells or other places, comprising a pump casing with a cylinder therein having an outlet at the lower end, a reciprocatory piston in the cylinder provided with a valve for controlling the outlet of the cylinder, a pipe 75 communicating with the cylinder below the piston, another pipe communicating with the cylinder above the piston, means for supplying the first-named pipe and portion of the cylinder below the piston with an explosive mixture, means for supplying the second-named pipe and portion of the cylinder above the piston with air under pressure, and means in the first-named pipe for igniting the explosive charge in said pipe for conveyance of 80 the ignition to and into the cylinder below the piston. 85

11. An apparatus for raising water from wells or other places, comprising a pump casing with a cylinder therein having an outlet at the lower end, a reciprocatory piston in the cylinder provided with a valve for controlling the outlet of the cylinder, a pipe 90 communicating with the cylinder below the piston, another pipe communicating with the cylinder above the piston, means for supplying the first-named pipe with an explosive mixture, means for supplying the second-named pipe with air under pressure, and means in the first-named pipe for igniting the explosive charge in said pipe for conveyance of 95 the ignition to the cylinder below the piston, said second-named pipe being provided with a cut-off valve communicating with and operated by pressure established in 100 the first-named pipe. 105

12. In an apparatus for raising water from wells or other places, a cylinder having an outlet at one end, a reciprocatory piston within the cylinder provided with a valve for controlling the outlet of said cylinder, means for supplying an explosive mixture to the cylinder on the valve side of the piston, and means for supplying air under pressure to the cylinder on the other 115 side of the piston to an extent to counteract the effect of the pressure of the explosive mixture before and after the explosion. 120

13. In an apparatus for raising water from wells or other places, a cylinder having an outlet at the lower end, a piston within the cylinder and provided with a valve for controlling the outlet, said piston having ducts therethrough for lubricant and opening in the cylinder at the end of the piston 125 130

remote from the valve, means for supplying an explosive mixture under pressure to the cylinder on the valve side of the piston, and means for supplying air under pressure to the cylinder on the side of the piston remote from the valve, said last-named means being utilizable for the introduction of lubricant into the cylinder for distribution through the ducts in the piston.

10 14. In an apparatus for raising water from wells or other places, a cylinder having an opening at one end and adapted to be immersed in the water in the well, a piston in the cylinder having a valve for controlling the opening in the cylinder, a pipe for introducing into the cylinder an explosive mixture under pressure on that side of the piston having the valve, and a pipe for introducing into the cylinder air under pressure on the side of the piston remote from the valve, said pipes having check valves therein adjacent to the cylinder and opening theretoward.

15 15. An apparatus for raising water from wells or other places comprising a pump casing adapted to be immersed in the water in the well, said casing having upright cylinders therein each with an outlet at the lower end and the casing having compartments therein individual to the cylinders, a foot valve for each compartment in line with the outlet of the respective cylinder and with each foot valve having a float tending to open the foot valve, a pipe communicating with both compartments and constituting the discharge pipe of the pump, said discharge pipe having a valve opening away from the compartments, a piston in each cylinder having a valve for controlling the

outlet of the cylinder, a pipe individual to each cylinder for supplying an explosive mixture under pressure to the cylinder on the valve side of the piston, another pipe for supplying air under pressure to both cylinders simultaneously on the side of the piston remote from the valve, said pipes leading to the top of the well, and means at the top of the well for igniting the explosive mixture in the pipes carrying it, whereby said pipes become fuse pipes for igniting the explosive mixture within the cylinders.

16. In an apparatus for raising water from wells and other places, an explosion chamber having a valved outlet, means for maintaining the valved outlet closed against a predetermined pressure, a pipe entering the explosion chamber and extending to a distance and provided with check means for preventing return flow of fluid under pressure from the explosion chamber to the pipe, means for supplying an explosive mixture through the pipe into the explosion chamber, and means for igniting the explosive mixture in the pipe on the side of the check means remote from the explosion chamber, whereby a progressive ignition of the explosive mixture occurs in the pipe, thereby recompressing the compressed explosive mixture within the explosion chamber before ignition thereof.

In testimony, that I claim the foregoing as my own, I have hereto affixed my signature in the presence of two witnesses.
